UNITED STATES PATENT OFFICE.

BENJAMIN F. PERRY, OF ELWOOD, INDIANA.

FOLDING CASTER.

1,033,267.

Specification of Letters Patent.

Patented July 23, 1912.

Application filed May 16, 1912. Serial No. 897,810.

To all whom it may concern:

Be it known that I, BENJAMIN F. PERRY, a citizen of the United States, residing at Elwood, in the county of Madison and State of Indiana, have invented certain new and useful Improvements in Folding Casters; and I do declare the following to be a full, clear, and exact description of the invention, such as will enable others skilled in the art 10 to which it appertains to make and use the same.

This invention relates to improvements in folding casters.

One object of the invention is to provide a 15 folding caster designed particularly for use on the legs of stoves or other heavy objects which are only occasionally moved.

Another object is to provide a caster of the character described having an improved 20 means for attaching the same to the leg of the object, whereby, the caster is firmly held in both an operative and inoperative position.

With these and other objects in view, the 25 invention consists of certain novel features of construction, combination and arrangement of parts as will be more fully described and particularly pointed out in the appended claim.

30 In the accompanying drawings; Figure 1 is a vertical sectional view of a stove leg showing my improved caster applied thereto; Fig. 2 is an inner side view of the same; Fig. 3 is a perspective view of the caster removed.

Referring more particularly to the drawings 35 Figure 1 denotes a stove leg on the inner side of which and at an equal distance from its lower end is formed an apertured bearing lug 2. Also formed on the inner side of the leg below the lug 2 and at a short distance above the lower end of the leg is a lower caster retaining lug 3. Also formed on the inner side of the leg above the lug 2 and 45 spaced the same distance therefrom as the lower retaining lug 3 is an upper caster retaining lug 4. To the lug 2 is pivotally connected the bifurcated upper end of a caster standard 5 to the lower end of which is swiveled a head 6 having thereon parallel 50 apertured ears 7 in which is revolvably mounted the caster wheel or roller 8. It will be noted by reference to Fig. 1 that the head 6 is formed at a slight angle to overcome the 55 angular position of the standard 5 when swung down to an operative position in the

leg 1 thus holding the wheel or roller 8 perpendicular with the floor or surface with which the same is engaged.

In the standard 5 at a suitable distance 60 from the pivotal connection thereof with the lug 2 is a slot 9 which when the standard is swung downwardly to bring the roller to an operative position is adapted to receive the retaining lug 3 which projects entirely 65 through the standard as shown. Adapted to be engaged with the projecting end of the lug 3 is a cotter pin or other suitable fastening 10 which is adapted to hold the standard 5 in engagement with the lug 70 thereby holding the roller in position to support the stove and to permit the latter to be readily moved from place to place. When not in use the standard 5 and roller or caster 8 are adapted to be folded upwardly within 75 the upper portion of the leg and to an out of the way position as shown in dotted lines in Fig. 1 and when thus swung upwardly, the slot 9 in the standard is projected into engagement with the upper retaining lug 4 in which position the standard is held by means of a cotter pin or other suitable fastening 11 which is inserted through the projecting outer end of the lug 4 as shown. 80

By constructing and arranging my improved caster as herein shown and described, it will be seen that when it is desired to move the object to which the same is applied, it is simply necessary to lift first one 90 end and then the other of the object to a sufficient extent to permit the standards 5 of the rollers to be swung down to operative positions and fastened in the manner described, whereupon, the object may be rolled to the desired position after which the ends are again lifted and the standards swung upwardly and fastened in inoperative positions, whereupon, the supporting legs of the object will be engaged with the floor. While 95 I have herein shown and described the caster as being applied to a stove leg, it will be obvious that the same may be applied to articles of furniture or other objects. 100

From the foregoing description, taken in 105 connection with the accompanying drawings, the construction and operation of the invention will be readily understood without requiring a more extended explanation.

Various changes in the form, proportion, 110 and the minor details of construction may be resorted to without departing from the

principle or sacrificing any of the advantages of this invention, as defined in the appended claim.

Having thus described my invention,
what I claim is:

The combination with a supporting leg having thereon an apertured bearing lug and upper and lower standard retaining lugs, of a caster standard pivotally connected at its inner end to said bearing lug and having therein a slot adapted to be brought into engagement with said retaining lugs when said standard is swung to operative and inoperative positions, leg fas-

tening pins adapted to be engaged with said retaining lugs, whereby said standard is held in engagement therewith, a head swiveled on the outer end of said standard, and a caster wheel revolvably mounted in said head.

In testimony whereof I have hereunto set my hand in presence of two subscribing witnesses.

BENJAMIN F. ^{his} X PERRY.
